ASSEMBLY OF ELECTRIC EXPLOSION
INITIATORS

Daniel D. Huyett, Wilmington, Del., assignor to
Atlas Powder Company, Wilmington, Del., a
corporation of Delaware

Application May 10, 1946, Serial No. 668,979

9 Claims. (Cl. 86—1)

1

This application relates to electric explosion initiators.

An object of the invention is the provision of an improved method for manufacturing leg wire and plug assemblies for electric explosion initiators.

Another object of the invention is the provision of a method for manufacturing highly water-resistant leg wire and plug assemblies for electric explosion initiators.

A further object of the invention is the provision of a method for manufacturing highly water-resistant electric explosion initiators.

Other objects will appear from the following description.

Electric explosion initiators such as electric detonators and electric squibs are usually made in the form of tubular shells closed integrally on one end, charged with explosive, and closed on the other end by means of plugs through which run leg wires. To provide adequate protection for the explosive it is important that the plugs be water-resistant and that they join the shell walls and embrace the leg wires in sealing engagement.

While closure plugs have been made from many different substances, rubber-like materials have found considerable application for this purpose largely because of the ease with which they may be crimped into initiator shell mouths to provide water-proof shell-to-plug seals.

Several different methods have been proposed for sealing leg wires into rubber-like plugs. According to one method, wires coated with a sealing material such as rubber cement are threaded through bored plugs. It has been found difficult, however, to obtain seals of adequate effectiveness with this method.

According to another method the rubber-like plugs are molded or vulcanized directly around the leg wires. This method often provides a good seal, but it suffers from the disadvantage of requiring a cumbersome molding and vulcanizing operation for each individual plug.

The present invention provides a readily manufactured plug and leg wire assembly which when combined in an electric explosion initiator produces an assembly of highly water-proof character.

According to the present invention, a bore through a rubber-like plug is held in expanded condition by means of a hollow needle containing a leg wire larger than the normal size of the bore, and the needle and the plug are then disengaged permitting the plug bore to shrink and

2

grip the leg wire. The elastic nature of the plug provides an exceedingly tight seal. The plug and leg wire assembly so produced is then preferably crimped to a metal initiator shell.

5 The invention will be more specifically described in connection with the drawing which sets forth a preferred embodiment and in which Figure 1 is a longitudinal view, partly in section, of a plug.

10 Figure 2 is a longitudinal view, partly in section, of two needles held in a base member.

Figure 3 is a longitudinal sectional view of a plug held in expanded condition by the two needles of Figure 2.

15 Figure 4 is a longitudinal view, partly in section, of the completed leg wire and plug assembly, and

Figure 5 is a longitudinal view, partly in section, of a completed electric detonator.

20 Figure 1 of the drawing shows a cylindrical neoprene plug 11 about 0.255 inch in diameter, about $\frac{7}{16}$ inch long, and provided with two longitudinal bores 13 and 15 each about 0.022 inch in diameter and spaced about $\frac{3}{32}$ inch apart, center-to-center.

25 In Figure 2 are shown two needles 17 and 19 provided with hollow portions 21 and 23, respectively, and held in upright position by support member 25 containing pins 27 and 29 which fit inside respective hollow portions 21 and 23. Needles 17 and 19 are each 0.072 inch in outside diameter along their shank portions and hollow portions 21 and 23 are each 0.054 inch inside diameter.

30 In the manufacture of the plug and leg wire assembly, neoprene plug member 11 is placed on needles 17 and 19 so that the points of the needles enter bores 13 and 15, and plug 11 is then forced down over needles 17 and 19 until it reaches support 25. Since needles 17 and 19 are larger in diameter than bores 13 and 15, it is readily seen that bores 13 and 15 are forced into expanded condition. The points on needles 17 and 19 are rounded as shown on the drawing, for it has been found that rounded points assist greatly in

35 entering the needles in the plug bores.

40 After plug 11 has been brought down to the bottom of the shanks of needles 17 and 19, support member 25 bearing pins 27 and 29 is removed from the needles and leg wires 31 and 33 bearing insulation 35 and 37, respectively, are inserted into hollow portions 21 and 23 of the needles 17 and 19. Wires 31 and 33 are 0.025 inch in diameter and insulation 35 and 37 is

45 in each case 0.049 inch in outside diameter. After

50 55

After plug 11 has been brought down to the bottom of the shanks of needles 17 and 19, support member 25 bearing pins 27 and 29 is removed from the needles and leg wires 31 and 33 bearing insulation 35 and 37, respectively, are inserted into hollow portions 21 and 23 of the needles 17 and 19. Wires 31 and 33 are 0.025 inch in diameter and insulation 35 and 37 is in each case 0.049 inch in outside diameter. After

wires 31 and 33 have been inserted into hollow portions 21 and 23, needles 17 and 19 are withdrawn from plug 11. Needles 17 and 19 are provided with indented portions 39 and 41, respectively, to provide an easy means for gripping them to pull them from plug 11. Since bores 13 and 15 are normally much smaller than either wires 31 and 33 or insulation 35 and 37, it may be seen that as needles 17 and 19 are withdrawn from, and the ends of their shanks pass through, plug 11, bores 13 and 15 spring back and contract tightly around the leg wires and their insulation. The final leg wire and plug assembly is shown in Figure 4.

Figure 5 shows a finished detonator. Electric match 55 is soldered to leg wires 31 and 33. The resulting plug, leg wire, and match assembly is inserted into charged gilding metal initiator shell 43 containing the conventional base charge 49, primary charge 51 and flash charge 53. As a final step, shell 43 is crimped into plug 11 by means of crimps 45 and 47 to complete the assembly. Crimps 45 and 47 not only hold plug 11 in shell 43 and provide a shell closure between plug and shell, but they also greatly increase the tenacity with which wires 31 and 33 are held in plug 11.

Detonators closed as just described have been found to be water-proof under 250 pounds per square inch of water pressure held for sixteen hours at 125° F. and under 50 pounds per square inch of water pressure held for four hours at 32° F.

It will often be found desirable to moisten the plugs and needles with glycerine or other lubricant to permit easier expansion of the bores. It is also often advantageous to dip the wires in sealing material such as rubber solvent or rubber cement prior to inserting them in the hollow portions of the needles. It is found that when cement is placed on the wires in this manner it tends to seal the joint between the insulation and the wire when the plug bore contracts a joint where lack of water-resistance has often been evidenced heretofore.

While neoprene is a preferred plug material, other rubber-like substances may be used with entirely satisfactory results. Natural rubber or various synthetic rubbers such as buna and butyl rubber, for example, may be used in the invention.

Plug material is readily supplied in long lengths extruded so as to provide the desired bores. When plug material is obtained in this form it is conveniently cut to the desired plug length after the needles have been partially inserted into the bores.

Plug and wire assemblies of the invention may be used with ignition means of various types. In addition to the match type, bridge plug or bead types may be employed, for example.

It is usually preferred to employ insulated wire in the assemblies of the invention, but the invention will also be found applicable to use with bare wires. When insulated wire is employed, the insulation may extend right through the plug or only part-way through as shown in the specific embodiment described above.

Insulation may be of many different types. As examples may be listed ethyl cellulose, vinyl halide, nylon compositions, and fabric or enamel insulations of various sorts.

Many different shell materials may be employed in the manufacture of initiators according to the invention. Usually gilding metal or aluminum

shells are preferred, but other metal or plastic materials may be used. Any effective number or forms of crimps may be used in accordance with the invention.

The invention may be performed equally well if the plug is moved over the needles or the needles are moved through the plug. Also it is not imperative that two needles be employed. The wires may be inserted separately, or a single hole plug may be supplied with a single or a bifilar wire in accordance with the invention.

What is claimed is:

1. A process for making a plug and leg wire assembly for electric explosion initiators which comprises providing a rubber-like plug having a bore smaller than the diameter of a flexible leg wire, expanding said bore with a hollow needle, the hollow portion of which is large enough to contain said leg wire, providing that said leg wire extends in said hollow needle sufficiently far that it also extends through said plug, then holding said plug and said leg wire stationary relative to one another, and moving said plug and said needle relative to one another and in the same relative direction as was employed in expanding said bore whereby the passage of said needle through said plug is completed and said plug bore shrinks and grips said leg wire.

2. A process according to claim 1 wherein said plug is neoprene.

3. A process according to claim 1 wherein said leg wire is insulated and it is provided that said insulation extends at least part way through said plug.

4. A process according to claim 1 wherein said leg wire is insulated, it is provided that said insulation extends part way through said plug, and said wire is coated with sealing material prior to being gripped by said plug.

5. A process for making an electric explosion initiator which comprises making a plug and leg wire assembly according to the process of claim 1, inserting said plug and leg wire assembly in the mouth of the initiator shell and crimping the walls of said shell into said plug.

6. A process for making an electric explosion initiator which comprises making a plug and leg wire assembly according to the process of claim 1 wherein said plug is neoprene, inserting said plug and leg wire assembly in the mouth of the initiator shell and crimping the walls of said shell into said plug.

7. A process for making an electric explosion initiator which comprises making a plug and leg wire assembly according to the process of claim 1 wherein said leg wire is insulated and it is provided that said insulation extends at least part way through said plug, inserting said plug and leg wire assembly in the mouth of the initiator shell and crimping the walls of said shell into said plug.

8. A process for making an electric explosion initiator which comprises making a plug and leg wire assembly according to the process of claim 1 wherein said leg wire is insulated, it is provided that said insulation extends part way through said plug and said wire is coated with sealing material prior to being gripped by said plug, inserting said plug and leg wire assembly in the mouth of the initiator shell and crimping the walls of said shell into said plug.

9. A process for making an electric explosion initiator which comprises providing a rubber-like plug having two bores; providing two flexible insulated leg wires, each of said bores being smaller

than the diameter of said leg wires, expanding each of said bores with a separate hollow needle, the hollow portion of each needle being large enough to contain one of said leg wires, coating each of said leg wires with sealing material, inserting each of said leg wires separately into one of said hollow needles sufficiently far that each leg wire extends through said plug and the insulation on each leg wire extends part way through said plug, then holding said plug and said leg wires stationary relative to one another, moving said plug and said needles relative to one another and in the same relative direction as was employed in expanding said bore whereby the passage of said needles through said plug is completed and said plug bores shrink and grip said leg wires, inserting the plug and leg wire assem-

bly, so produced, in the mouth of an initiator shell, and crimping the walls of said shell into said plug.
